UNITED STATES PATENT OFFICE

147,723

DESIGN FOR A BEAUTY SHOP POLE

James E. Garris, Washington, D. C.

Application January 25, 1946, Serial No. 125,974

Term of patent 7 years

(Cl. D1—12)

To all whom it may concern:

Be it known that I, James E. Garris, a citizen of the United States, residing in Washington, in the District of Columbia, have invented a new, original, and ornamental Design for a Beauty Shop Pole, of which the following is a specification, reference being had to the accompanying drawing, forming part thereof, in which:

The dominant features of my design reside in the portions shown in full lines.

I claim:

The ornamental design for a beauty shop pole, as shown and described.

JAMES E. GARRIS.
